Whole No. 1472

Elias Ingraham, of Bristol, Conn.
Letters Patent No. 107, dated Sept. 3, 1861.

The schedule referred to in these Letters Patent and making part of the same.

To all whom it may concern:

Be it known that I, Elias Ingraham, of Bristol, County of Hartford and State of Connecticut, have invented or produced a new and original design for a Clock Case, and I do hereby declare that the following is a full and exact description of the same, referring to the photographic views, in which the same letters indicate like parts.

For the accompanying photographic views is shown a new and original design for a clock case.

A, is the base of the case, B, are square edge sides of the case, C, is the square edge, oblique, or double slant Top, of the case, configurated with a half bead D, on its edges. E, is a recess surface, F, is the dial, G, is the dial sash. the whole combined to produce a plain ornamental design for a clock case.

What I claim therefore and desire to secure by Letters Patent is the design for a clock case as herein above illustrated and set forth.
